ILLUMINATION TUBE

Eugene A. Giard, Milwaukee, Wis., assignor to
 Cutler-Hammer, Inc., Milwaukee, Wis., a corporation of Delaware

Application April 20, 1933, Serial No. 667,019

7 Claims. (Cl. 176—124)

This invention relates to improvements in gaseous illuminating tubes employed for lighting effects.

An object of the invention is to provide a tube 5 which will respond to an ignition voltage lower than the normal operating voltage of the tube.

Another object is to provide a gaseous illuminating tube, the light emission or brilliancy of which can be varied within very wide limits 10 by varying the voltages impressed upon the tube.

Another object is to provide a tube which yields a steady light for a wide range of brilliancy.

Another object is to provide a tube which emits a steady light from a very low to the highest 15 brilliancy at which the tube operates.

Other objects and advantages of the invention will hereinafter appear.

The ordinary neon or other gaseous tube is equipped with two cold electrodes and initiation 20 of discharge therebetween depends upon the presence of a few ionized molecules which are present in the tube at all times and which permit initiation of discharge through the tube when the potential difference between the electrodes is sufficiently high. If the tube is supplied with current 25 from an alternating current source, the discharge is started during each half cycle at a moment when a sufficient voltage exists between the electrodes to produce adequate additional ionization of the 30 gas to maintain an arc. The voltage which is necessary to maintain the gas column between the electrodes ionized or in the conducting state, is usually appreciably less than that which is required to start the ionization or discharge.

If an attempt is made to reduce the voltage 35 applied to the tube after the arc has started, for the purpose of reducing the luminosity of the arc, the arc is extinguished and is not ignited again until the voltage reaches a higher value.

The voltages at which this occurs are not always 40 the same, on account of the random ionization of the gas in the neighborhood of the electrodes and also due to voltage fluctuations and transient voltages on the supply lines. It has, therefore, 45 not been possible, in the past, to dim neon and similar tubes from full brilliancy to black or vice versa. Ordinary gas tubes flicker when operating at their lowest brilliancy, because at the start of each half cycle of the voltage is necessary to

50 ionize enough gas to start the arc, and due to irregularities the arc does not always start at the same voltage. Hence its establishment at the lower operating voltage is not certain and this causes flickering.

55 The present invention avoids this instability by

providing a definite and controlled quantity of ionized gas around the main electrodes prior to the establishment of the arc between the main electrodes.

The accompanying drawing illustrates diagrammatically one embodiment of my invention. 5

In the drawing, 1 is a gaseous luminous tube having at its ends enlargements 2 and 3 in which are mounted main electrodes 4 and 5, respectively, and auxiliary electrodes 6 and 7, respectively. 10 These electrodes may be of any suitable form. Connected between the auxiliary electrodes 6 and 7 is a resistor 8 of high ohmic value. A transformer 9 has its primary winding 10 connected across alternating current supply lines 11 and 12 15 in series with a regulating impedance 13, the secondary winding 14 of said transformer being connected between the main electrodes 4 and 5.

The operation of the tube is as follows: When 20 voltage is supplied to the transformer 10 and said voltage is gradually raised from a minimum by adjustment of the impedance 13, a point is reached where the gas between the electrodes 4—6 and 5—7, respectively, at the two ends of the tube becomes sufficiently ionized to sustain 25 a continuous discharge in the two ends of the tube, current flowing from the winding 14 between the electrodes 4 and 6 through the resistance 8, between the electrodes 7 and 5 back to the winding 14, or in the opposite direction during 30 alternate half cycles. This discharge, which is limited by the high resistance 8, provides a supply of ionized molecules around the main electrodes tending to ionize additional gas molecules by impact. Further increase in the applied voltage 35 so increases the number of these ionized molecules that they are forced more and more into the cylindrical main portion of the tube, until the luminous columns emerging from both ends fill the entire central part of the tube. The 40 intensity of the light under these conditions is very low compared to the minimum intensity of the light which can be maintained continuously in an ordinary luminous tube without the auxiliary electrodes. 45

Further increase of the voltage impressed upon the main electrodes increases the intensity of the light emitted from the main column, while the discharge in the tube ends between the main and auxiliary electrodes remains apparently the 50 same. It is thus possible to vary the light intensity furnished by the tube from a very low intensity to maximum intensity corresponding to the maximum current which the tube is capable of carrying and the minimum intensity of the 55

light column at which the tube can be operated with a steady light emission is very much lower than the minimum intensity of an ordinary tube when operated without flickering.

5 As aforescribed, the resistance θ should be as high as possible, permitting just a sufficient amount of discharge between the respective main and auxiliary electrodes to supply an adequate amount of ionization for the formation of the 10 main light column.

10 The voltage impressed upon the main electrodes may, of course, be varied in any other suitable manner and it is also possible to operate the tube with a variable voltage direct current 15 in which case the auxiliary electrode, at the positive end of the tube, may be omitted and the resistance θ be joined directly to the main anode.

15 The main body of the tube need not be cylindrical as shown in the drawing, but may assume 20 any other desired form suitable for the purpose.

It is obvious that a single gas or a mixture of gases or a vapor or mixture of vapors and/or gases may be employed in the tube described.

What I claim as new and desire to secure by 25 Letters Patent is:

1. A luminous gas discharge tube, comprising a glass tube having enlarged electrode chambers, a main electrode and an auxiliary electrode within each chamber and a relatively high impedance 30 arranged externally of said tube and connected in circuit between said auxiliary electrodes.

2. A luminous gas discharge light, comprising a glass tube having enlarged electrode chambers and a restricted passage therebetween, an attenuated gas in said tube, a main electrode and an auxiliary electrode wholly within each chamber of said tube and a relatively high impedance arranged externally of said tube and connected in circuit between said auxiliary electrodes.

3. A luminous gas discharge light, comprising an hermetically sealed glass tube having enlarged electrode chambers and a restricted passage therebetween, an attenuated gas in said tube, a main electrode in each chamber of said

tube adapted to be connected respectively to opposite poles of a power supply, an auxiliary electrode wholly within each chamber, and a relatively high impedance series connection between said auxiliary electrodes arranged externally of 5 said tube.

4. A luminous gas discharge light, comprising an hermetically sealed glass tube having an enlarged electrode chamber at each end and a restricted passage therebetween, an attenuated gas 10 in said tube, a main electrode in each chamber adapted to be connected respectively to the poles of a power supply, an auxiliary electrode wholly within each chamber and an external relatively high impedance series connection for said aux- 15 iliary electrodes.

5. A luminous gas discharge light, comprising an hermetically sealed glass tube having an enlarged electrode chamber at each end and a restricted passage therebetween, an attenuated gas 20 in said tube, a main electrode in each chamber adapted to be connected respectively to the poles of a variable voltage source of power, an auxiliary electrode wholly within each chamber and an external series connection for said auxiliary 25 electrodes of relatively high impedance.

6. A luminous gas discharge tube, comprising a glass tube having in a spaced relation enlarged electrode chambers, main electrodes within said chambers for emitting a discharge and auxiliary 30 electrodes through which the discharge between said main electrodes, in part, passes, said auxiliary electrodes being arranged wholly within the chambers of their respective main electrodes.

7. A luminous gas discharge tube, comprising 35 a glass tube having in a spaced relation enlarged electrode chambers, a main electrode and an auxiliary electrode in each chamber, a relatively high impedance external to said tube, said auxiliary electrodes being wholly within their respective chambers and being adapted to pass a current between said main electrodes and through 40 said impedance.
